UNITED STATES PATENT OFFICE.

HOWARD A. DUCHEMIN, OF LOS ANGELES, CALIFORNIA.

METHOD OF BUILDING HOLLOW-WALL CONSTRUCTIONS.

Application filed October 13, 1924. Serial No. 743,337.

This invention relates to improvements in methods for building hollow wall constructions.

It is an object of this invention to provide a method whereby a hollow wall may be easily, cheaply and quickly constructed. The method consists essentially of forming the hollow wall in a substantially horizontal position, and after the hollow wall has 10 become cured, elevating it into its vertical position.

With the foregoing and other objects in view which will be made manifest in the following detailed description and pointed out in the appended claims, reference is had to the accompanying drawings for an illustrative embodiment of the invention, wherein:

Figure 1 is a perspective view showing 20 the initial steps in constructing the hollow wall,

Fig. 2 is a perspective view showing the wall as having been further formed,

Fig. 3 is a perspective view showing the 25 wall in its upright position,

Fig. 4 is a vertical section taken substantially on the line 4—4 of Fig. 3, and

Fig. 5 is a horizontal section taken substantially on the line 5—5 of Fig. 3.

Referring to the accompanying drawings wherein similar reference characters designate similar parts throughout, it will be understood that the hollow wall may be formed on any substantially horizontal flat 35 surface. In the drawings I have illustrated the wall as being formed upon a platform formed by suitable planks 10 supported upon suitable struts 11. A pair of end rails 12 are placed upon the platform and serve 40 to define the width of the section of wall to be formed. A pair of rails 13 are also placed upon the platform and serve to define the height of a wall section to be formed. The rails 13 are of a depth equal to the thickness 45 of one face of the wall.

Between the end rails 12 and the rails 13, concrete is poured and leveled off even with the tops of the rails 13. This material provides for one face of the hollow wall. When 50 this has been completed, suitable wedges 14, which may be in the form of planks wedge-shaped in cross section or may be simply small wedges of a few inches in breadth, are placed upon the rails 13 at various intervals. Center pieces 15 which carry suitable

stringers 16 secured upon their sides are placed upon the wedges 14 as illustrated in Fig. 2. Side pieces 17 which are provided with similar stringers 18 are also laid upon the rails 13. Top pieces 19 which may be 60 in the form of planks are then placed between the center pieces 15 and the side pieces 17 and rest upon the pieces 16 and 18. The wedges 14, the center pieces 15, the side pieces 17, and the top pieces 19 all 65 constitute a plurality of separate collapsible forms which provide for openings extending longitudinally through the wall. Concrete or other plastic material is then poured about the forms so provided so as to fill the 70 openings left between adjacent side pieces 17. Additional concrete or similar material is then poured upon the top of the forms, as at 20, and is leveled off so as to provide the other face of the wall of the 75 desired thickness.

It will readily be understood that the ends of the openings provided between the adjacent side pieces 17 may be closed by suitable blocks, or in any other convenient 80 manner, which will prevent the concrete or plastic material from running out of the openings between the side pieces 17, and keeping the top material 20 from running off from the platform. In the present instance, suitable planks, as at 21, are secured over the rails 13 which close the opening between the side pieces 17 and cooperate with the end rails 12 to prevent the top 85 concrete 20 from flowing off from the platform. 90

The wall so formed is allowed to set and become cured; and after this has been done, the pieces 21, the end rails 12 and the rails 13 are all removed. Before removing the 95 rails 13, the wedges 14 are knocked out from under the center pieces 15, enabling the center pieces to fall and to be withdrawn from the openings provided in the wall. After these center pieces 15 have been removed, 100 the top pieces 19 may be withdrawn and the side pieces 17 may be turned over flatwise and removed from the openings. It will be noted that the upper edges of the side pieces 17 are beveled, as at 17^a, to facilitate 105 withdrawing these pieces from the webs 22 formed between the faces 23 and 24 of the wall.

After the forms have been removed, the 110 wall is then elevated into its upright posi-

tion, as shown in Fig. 3, either by jacks or a derrick, or any other suitable means. When the wall is in its upright position, grout is poured into the openings provided in the wall so as to fill up the bottoms of these openings, as indicated at 25. By pouring the grout in the openings, a bind or tie is formed between the wall and the surface upon which it rests. This grout also serves to aid in maintaining the wall in upright position.

As illustrated in Figs. 1 and 2, the faces of the wall, 23 and 24, may be reinforced as by reinforcing wire 25 and 26. Suitable reinforcing rods 27 and 28 may also be provided which are preferably positioned above and below the webs 22. The reinforcing wires 25 and the reinforcing rods 27 may be positioned upon the platform and the concrete which is poured upon the platform to form the face of the wall may be poured thereon, or the concrete may be first poured and the reinforcing material may then be imbedded therein.

25 It will readily be seen that the improved method of making a hollow wall consists essentially of forming the hollow wall in a substantially horizontal position and then raising the wall into its vertical position.

30 A window or door opening may be provided in the wall, as indicated upon the drawing, by merely placing small rails 30, which are the same depth as the end rails 13, upon the platform 10 before pouring the face 23. When the face 23 has been poured, the collapsible forms are placed upon the end rails 13, as before, and these forms extend over the opening provided by the rails 30. Rails 31 may be placed upon the collapsible forms and provide the opening in the face 24. The concrete is poured about the rails 30 and 31 and when the wall has been poured and cured, these rails may be readily removed, leaving the wall opening.

45 The various sections of the complete wall may be secured by providing suitable tie wires, as indicated at 32, upon the end faces of each section, which may be secured to tie wires of adjacent sections. Concrete may be poured between the end faces of adjacent sections or if the crack or opening between these sections is very small, the opening may be merely "pointed up" with a trowel.

55 It is to be understood that the collapsible forms may be made either of metal or of wood, and in the preferred construction, these forms are made of metal, for the reason that wood forms sometimes have the tendency to swell and cause trouble in the

withdrawing of the forms from the openings in the wall.

It will be understood that various changes in the detail of construction may be made without departing from the spirit or scope of the invention as defined by the appended claims.

I claim:

1. The method of building a hollow wall which consists of pouring a slab of self-hardening plastic material in a substantially horizontal position, supporting a plurality of rigid collapsible core forms at their ends in spaced parallel relation over said slab, pouring self-hardening plastic material between and over the core forms, collapsing and withdrawing the core forms when the material has set, and raising the wall from the horizontal position into a substantially vertical position.

2. The method of building a hollow wall which consists of pouring a slab of self-hardening plastic material upon a metallic reinforcement, so as to form a reinforced slab in an approximately horizontal position, supporting a plurality of rigid collapsible core forms at their ends in spaced parallel relation over said slab, pouring self-hardening plastic material between the core form, placing a metallic reinforcement over the core forms, pouring a self-hardening plastic material over the core forms, imbedding the metallic reinforcement therein, thus forming a second reinforced slab which is disposed over the core forms and connected to the first reinforced slab, collapsing and removing the core forms when the material has set, and raising the wall from the horizontal position into a substantially vertical position.

3. The method of building hollow walls which consists of pouring a slab of self-hardening plastic material in a substantially horizontal position, supporting a plurality of rigid collapsible core forms at their ends in spaced parallel relation over said slab, pouring self-hardening plastic material between and over the core forms, collapsing and withdrawing the core forms when the material has set, raising the wall from the horizontal position into a vertical position in such a manner that the openings previously occupied by the core forms would be arranged vertically and pouring grout into the openings through the upper ends.

In testimony whereof I have signed my name to this specification.

HOWARD A. DUCHEMIN.
